UNITED STATES PATENT OFFICE.

WILLIAM W. WINDLE, OF MILLBURY, MASSACHUSETTS.

ROTATING SCREEN.

No. 796,485.

Specification of Letters Patent.

Patented Aug. 8, 1905.

Application filed March 3, 1900. Serial No. 7,178.

To all whom it may concern:

Be it known that I, WILLIAM W. WINDLE, a citizen of the United States, residing at Millbury, in the county of Worcester and Commonwealth of Massachusetts, have invented a new and useful Improvement in Rotating Screens, of which the following is a specification, reference being had to the accompanying drawings, forming a part of the same, in which—

Figure 1 represents an end view of a rotating screen embodying my invention, the view showing the receiving end of the screen. Fig. 2 is a side elevation with the inclosing case removed on the line 2 2, Fig. 1. Fig. 3 is an end view showing the delivery end of the screen and represented in sectional view on line 3 3, Fig. 2; and Fig. 4 is a top view of a portion of the screen, showing the delivery end with the casing removed on line 4 4, Figs. 1 and 3.

Similar reference-letters refer to similar parts in the different views.

My invention relates to a rotating screen designed to remove dust and other impurities from the articles screened, and particularly from wool, cotton, and other fibrous material; and the object of my invention is to provide a screen for this purpose which shall be automatic in its action, and I accomplish these results by means of the construction and arrangement of parts as hereinafter described, and pointed out in the annexed claims.

Referring to the drawings, A denotes an inclosing case which, however, may be omitted, if desired. Contained within the chamber inclosed by the case A is a rotating screen, consisting in the present instance of a framework comprising the hexagonal heads B B', having circular openings B² and connected by the longitudinal strips or bars B³. The outer hexagonal surface of the frame is covered with wire-cloth or wire-netting C, having a suitable mesh to retain the fibrous material being screened and permit the escape of dust and other impurities. Surrounding the framework of the screen and attached thereto are rings D D and D', the rings D D being provided with flanges to hold the screen from longitudinal movement on its driving-pulleys, and each of the rings rests upon friction-rolls E, which are carried by parallel shafts E', journaled in bearings E², which are supported upon a framework F, resting at the end F' upon the floor and supported at the end F² upon wedges F³, which are arranged to slide upon ways F⁴ and are actuated by a screw-threaded shaft F⁵, having at its center a hub F⁶, pro-

vided with holes to receive a spanner by which the screw-threaded shaft may be rotated in order to separate the wedges or draw them nearer together. The purpose of the sliding wedges F³ is to elevate the end F² of the supporting-frame F, and thereby incline the axis of the rotating screen by raising the receiving end of the screen higher than the delivery end, so that as the wool or other fibrous material is placed within the screen at the highest or receiving end it will be gradually moved lengthwise the screen by gravity as the screen is rotated. A series of pins G are inserted in back of the longitudinal bars B³ at a slight angle to a radial line, the pins being inclined in the direction in which the screen rotates, as indicated by the arrow 1; so that the material to be screened will be caught by the inclined pins G and carried from the bottom of the screen to the top, where it slides off the pins G and falls by gravity to the bottom of the screen. The continued concussion of the fibrous material against the bottom of the screen as it is raised and allowed to fall causes the dust to be liberated and fall through the meshes of the wire-cloth C upon an apron H, which is curved concentrically with the axis of the screen and arranged to gather the dust falling through the meshes of the screen. The rotating screen carries a longitudinal blade I, extending the entire length of the screen, the blade projecting radially beyond the rings D D' far enough to sweep the dust gathered on the apron H off the end H' and allow it to fall by gravity through a chute H².

As the fibrous material is carried by the pins G to the top of the screen and allowed to fall it will be carried by gravity in a vertical line to the bottom of the screen, and as the axis of the screen is raised at the receiving end the falling material will drop each time upon the bottom of the screen at a point slightly nearer the delivery end of the screen, the distance being determined by the inclination of the axis of the screen. The time required to move the fibrous material from the receiving end to the delivery end of the screen can therefore be varied by the operator by raising or lowering the receiving end of the screen by means of the sliding wedges F³.

At the delivery end of the screen I provide a circular drum J concentric with the circular opening B' at the delivery end of the screen, into which the material is delivered from the screen as it rotates. The drum J is closed at its outer end, but open at its inner

end or end next the screen and is provided with an inclined spout J^2 . Attached to the head B' at the delivery end of the screen are blades J^4 , parallel with the axis of the screen and projecting into the drum J and arranged to sweep the interior of the drum and push the fibrous material after it has been screened through the opening J' either upon the floor or through a vertical chute. (Indicated by the broken lines J^3 , Figs. 2 and 3.) The shafts E' are rotated by means of the gears KK , engaging a gear K' on a counter-shaft K^2 , which carries the tight and loose pulleys $K^3 K^4$ and is driven by a belt connection with a main driving-shaft.

The sleepers $F F$, composing the frame, are extended rearwardly and are adapted to support the hanger L , in which are journaled the ends of the shafts $E' E'$ and the shaft K^2 , carrying the pulleys $K^3 K^4$. Thus when the wedges $F^3 F^4$ are operated against the inclined lower faces of the front ends $F^2 F^2$ of the frame F , which front ends are cut away to receive the wedges, the frame F and its connected parts is raised or lowered on its ends $F' F'$ as fulcrums, the movement at the ends $F' F'$ being very slight, owing to the length of the machine.

The operation of my improved screen is as follows: The wool, cotton, or other fibrous material to be screened is placed in the screen through a circular opening in the head B at the receiving or highest end of the screen, and as the screen rotates the material is caught by the projecting pins G and carried in the direction of the arrow 1 to the top of the screen, from which it falls by gravity to the bottom to be again lifted as the screen rotates. As the end F^2 of the frame F is raised, by means of the sliding wedges F^3 , to give the proper inclination to the axis of the screen the fibrous material will be gradually carried toward the delivery end of the screen as it rotates, and the inclination given to the axis of the screen determines the time the material is subjected to the action of the screen, a sufficient time being allowed to thoroughly screen the dust and all impurities, which will pass through the meshes of the cloth from the material. In case the material delivered from the end of the screen is not sufficiently clean the wedges F^3 are moved outwardly to lower the axis of the screen at the receiving end, and thereby increase the time the fibrous material is subjected to the action of the screen before it is delivered into the drum. During the operation of screening not only dust and dirt but burs, short fibers of wool, and all particles which are small enough to pass

through the meshes of the wire-cloth C are extracted from the material and deposited upon the apron H , from which the accumulation is scraped by the blade I and delivered through the chute H^2 , while the cleaned material is caught in the drum J and delivered therefrom by the blades J' through the spout J^2 and chute J^3 . The apparatus is therefore entirely automatic in its action, and after having covered the revolving frame with a screen-cloth of suitable-sized mesh and adjusted the inclination of the axis of the rotating screen to cause the material to be retained until thoroughly screened the operation will be automatically continued by simply feeding material to the receiving end of the screen, and both the screened material and the impurities removed therefrom will be delivered through separate delivery-openings.

What I claim as my invention, and desire to secure by Letters Patent, is—

1. The combination with a rotating screen, of a frame capable of inclined adjustment, means on the frame for supporting and rotating the screen, the screen provided with inlet and discharge openings, a fixed drum located outside of and adjacent the discharge-opening and a blade carried by the screen and projecting longitudinally beyond its discharge end, the blade received within the independent fixed drum and adapted to scrape the interior thereof.

2. The combination with a rotating screen, of a frame capable of inclined adjustment, means on the frame for supporting and rotating the screen, the screen provided with inlet and discharge openings, a drum located outside of and adjacent the discharge-opening and a blade carried by the screen and projecting outside the discharge-opening and into the drum to scrape the interior thereof.

3. The combination with a rotary screen, of a frame, means carried by the frame for supporting and rotating the screen, the screen provided with inlet and discharge openings, a stationary drum located beyond the screen and adjacent the discharge end thereof, the drum adapted to receive the material delivered from the screen, a chute leading from the drum for the conveyance of the material therefrom and means for scraping the drum.

In testimony whereof I have signed my name to this specification, in presence of two subscribing witnesses, this the 28th day of February, 1900.

WILLIAM W. WINDLE.
